motor is ensured with no weight increase as compared with a water cooled gun, everything else being the same.

The supply pump 22 for the motor is placed, for instance, on the fixed stand which supports the reel 23 from which the wire 1 is led to the gun through the flexible sheath 2 (Figures 1 and 2). It is connected, on its suction side, at 24, with a cold water source of a suitable type and its delivery side is connected through any suitable flexible pipe 25 with the input 26 to the motor 21 placed on the gun and the output of which 27 is connected to the inside of the sleeve 9 (Figure 1). The pump 22 is driven by an electric motor 28 coupled with the pump either directly or through a suitable reducer.

In the case of the diagram of Figure 2, the wire 1 is wound off the reel 23 by the pull exerted by the rollers 5 and 6 mounted on the gun, but there may be provided, also, as in the case considered in the diagram of Figure 5, a pulling mechanism consisting, for instance, of two rollers 5a and 6a and placed between the wire reel 23 and the pulling rollers 5—6 provided on the gun. These rollers 5a—6a are placed, for instance, at the entrance to the flexible sheath 2 connected with the gun at 3a (Figure 1). In this case, the driving roller 5a is conveniently coupled with the shaft of the pump and the conditions are so determined that the speed of the linear displacement imparted to the wire 1 be the same at the outputs of each pair of rollers or that, preferably, the speeds at the output from the rollers 5a—6a be slightly less than that at the output from the rollers 5—6 on the gun.

The arrangement of the adjusting means for that speed varies according to whether a variable or constant speed electric motor 28 is used. In the first case it is sufficient to adjust the speed of this electric motor by means of any one of the devices already used in known arc welding stations.

If a constant speed electric motor is used, the following solutions may be used:

An adjustable output pump is used;

A constant output pump is used.

In the second case, the liquid flow rate delivered to the motor is varied by shunting the latter. It is possible, amongst other arrangements, to adopt that indicated in the diagram of Figure 3. In this arrangement, the hydraulic motor 21 is shunted by a derivation on which an automatic element is interposed for controlling the section of the passage offered to the liquid. This arrangement is constituted, for instance, by a differential piston 29—29a, one end 29a of which forms a valve movable with respect to a fixed seat 30. For a given pressure in the conduit 25 the piston is in equilibrium under the thrusts applied on each one of the two different areas 29 and 29a and by the spring 31. The reaction of the latter is adjusted by the screw 32 or other movable stop. This equilibrium position of the piston corresponds to a given opening of the valve 29a and consequently to a predetermined liquid flow rate through the conduits 25—13 and 33—33—33 and to a given speed of the motor. If the load applied to the latter varies, and if the speed of the motor tends to decrease or to increase in consequence, the pressure inside the conduit 25 rises or drops and the piston 29—29a is moved in the suitable direction for moving the flap 29a for bringing back the speed of the motor 21 to the set speed.

In case of an accidental blocking of the wire driving mechanism, and of a stopping of the motor 21, a delivery valve 34 loaded by an adjustable spring 35 allows the water to pass from the conduit 25 to the conduit 33 and to the cooling circuit for the gun.

The diagram of Figure 4 corresponds to that of Figure 3 but when unwinding rollers such as 5a—6a (Figure 5) are used at the outlet from the wire reel 23, these unwinding rollers being no longer driven by the pump 22 as

in the case of Figure 5 but by a motor 21a (Figure 4) identical with the motor 21 which drives the rollers 5—6 mounted on the gun. The two motors 21a and 21 are mounted in series in the delivery of the same pump 22 driven by the constant speed electric motor 28. The adjustment of the speed for the two motors simultaneously is effected by means of the differential piston 29—29a, the operation of which remains that described in connection with Figure 3. The same elements or corresponding elements are designated by the same reference numbers on all the figures in the drawings.

What I claim is:

1. In an electric arc-welding gun with a consumable electrode wire moved through the gun, a gun body provided with means for guiding the wire, with a mechanism for moving the wire and with means for supplying said wire with an electric welding current, a hydraulic gear motor mounted on said body and directly coupled with said mechanism, a volumetric pump remote from the gun body and having its outlet connected to the inlet of said hydraulic motor, an electric motor for driving the pump, and means for supplying said pump with a hydraulic fluid, said hydraulic fluid being used also as a cooling medium for the gun body.
2. In an electric arc welding gun with a consumable electrode wire moved through the gun, a gun body provided with means for guiding the wire, with a mechanism for moving the wire and with means for supplying said wire with an electric welding current, a hydraulic motor mounted in the body gun and operatively coupled with said mechanism, a hydraulic pump remote from the gun body, the outlet of said pump being connected to the inlet of said hydraulic motor, means for supplying said pump with a hydraulic fluid, a constant speed electric motor for driving the hydraulic pump, and a by-pass device adapted to shunt the hydraulic motor and including a valve responsive to the pressure of the fluid forced into the hydraulic motor by the pump for keeping constant the speed of said hydraulic motor.
3. In an electric arc-welding gun with a consumable electrode wire moved through the gun and fed to the latter by a mechanism driven by a variable speed electric motor, a gun body provided with a means for guiding the wire, with a mechanism for moving the wire and with means for supplying said wire with an electric welding current, a hydraulic gear motor mounted on said body and directly coupled with said mechanism, a volumetric pump remote from the gun body and having its outlet connected to the inlet of said hydraulic motor, said pump being driven by the electric motor provided for driving the mechanism which feeds the electrode wire to the gun body, and means for supplying said pump with a hydraulic fluid, said hydraulic fluid being also used as a cooling medium for the gun body.
